PADLOCK

Filed Nov. 17, 1937

FIG. 3

FIG. 1

FIG. 5

FIG. 4

A circular diagram representing a lock mechanism. The outer boundary is a thick line. Inside, there are several labeled parts: '34' at the top left, '24' and '25' at the top center, '30' and '31' on the left side, '18' on the bottom left, '22', '23', '47', and '48' on the right side, 'LOCK CO.' in the center, and '44', '16', '72', and '26' at the bottom. There are also three small circles near the bottom center.

PADLOCK

Harry E. Soref, Milwaukee, Wis., assignor to Master Lock Company, Milwaukee, Wis., a corporation of Wisconsin

Application November 17, 1937, Serial No. 175,003

5 Claims. (Cl. 70—38)

The invention relates to locks and more particularly to padlocks.

An object of the invention is to provide an improved lock structure of simple, durable and inexpensive construction, capable of easy assembly, and especially suitable for padlock use.

Another object of the invention is to provide a lock structure which can readily be assembled to produce various key changes, and which requires but relatively few parts.

The invention further consists in the several features hereinafter described and claimed.

In the accompanying drawing, illustrating an embodiment of the invention,

Fig. 1 is a front view of a padlock constructed in accordance with the invention;

Fig. 2 is a rear view thereof, parts being broken away and parts being shown in section;

Fig. 3 is another rear view, parts being removed and broken away and parts being shown in section;

Fig. 4 is a sectional elevation of the padlock, looking from the rear, and taken generally in the plane of the shackle, the shackle being open and a key being shown in unlocking position;

Fig. 5 is a sectional elevation taken generally along the line 5—5 of Fig. 1;

Fig. 6 is a sectional view taken generally along the line 6—6 of Fig. 4, the shackle being returned to locking position;

Fig. 7 is a front view of an inner lock case with attached parts;

Fig. 8 is a detail view of one of the locking levers, and

Fig. 9 is a detail view of one of the ward members.

In the drawing, 15 designates a lock case, here shown to be of cylindrical form and to have flat, parallel front and rear plates 16 and 17, respectively. The front plate 16 is preferably integral with the cylindrical portion of the case to form a cup, and the rear plate 17 marginally bears on the edge of the cup. The case 15 is enclosed by a cup-shaped shell 18 which fits closely thereto and has an outwardly dished front portion 19. Positioning nubs 20 on the front plate 16 enter embossments 21 on the front portion of the shell. An outwardly dished rear cover plate 22 marginally bears on the rear plate 17, and both of these plates are secured in place by a bead or flange 23 formed by spinning or curling over the rear edge of the shell. A positioning lug 24 on the edge of the rear plate fits in a notch 25, Fig. 2, in the edge of the cover plate. The various parts above described are conveniently formed of sheet

metal stampings. If desired, the rear plate 17 may be provided with a central projection 26, such as a stud riveted thereto, to support the dished portion of the cover plate 22.

A guide member 27, preferably in the form of a flat, sheet metal stamping, has a projection 28 at one side edge riveted or otherwise secured in an anchor slot 29 formed in the front plate 16, Fig. 7, and has a projection 30 at its other side edge which fits in a slot 31 in the rear plate 17, Fig. 2. The guide member extends across the space between the front and rear case walls and has formed therein a shackle-guiding opening 32, Fig. 4.

The case and shell have openings 33 therein to slidably receive the legs of a U-shaped shackle 34, the long leg of the shackle also slidably and rotatably passing through the guide member opening 32, and the short leg having a beveled end and a locking notch 35 near this end. An annular groove 36, Fig. 4, is formed about the end portion of the long shackle leg and slidably receives therein a forked stop plate 37 which is engageable with the guide member 27 to limit the outward movement of the shackle. The forked stop plate 37 is confined on the shackle leg by the slidable engagement of an edge of the plate with the flat inner face of the rear case plate 17.

The shackle is preferably spring-urged outwardly, as by means of a coiled compression spring 38 which enters the tubular end of the long shackle leg. The spring is guided by a headed stem 39 therein, the head of the stem resting in a positioning seat 40, Fig. 4, formed in a plate 41 which is secured in the case and is spaced downwardly from the guide plate 27. The plate 41 has a projection 42 at one side edge riveted or otherwise secured in an anchor slot 43 formed in the case front plate 16, Fig. 7, and has a projection 44 at its other side edge which fits in a slot 45 in the rear plate 17, Fig. 2. One end of the plate 41 has a downwardly offset portion 46 which forms a key-guiding ledge and stop.

A guide pin or stud 47 is rigidly riveted at one end on the front plate 16, and has its other end fitting in an opening 48, Fig. 2, formed in the rear plate 17, the pin extending at right-angles to the front and rear plates and being at the side portion of the case adjacent the short shackle leg.

Mounted on the guide pin 47 are a number of flat metal plates, six being shown by way of example, filling the depth of the case between the front and rear case plates. Two of these plates, 55

49 and 50, constitute locking members or bolts, and are in the form of tumbler-like levers pivotally mounted on the pin, each lever being provided with an opening 51 to receive the pin. Each locking lever has a hooked upper end 52 engageable with the notched end of the short shackle leg to thereby lock the shackle. Each locking lever is urged to locking position by a narrow leaf spring 53 which has a hooked end portion engaged in a pocket 54 in the lever, the other end portion of the spring slidably bearing against an edge of the guide plate 27, this edge being spaced from the pin 47 and extending parallel to the pin. The spring width is about the same as the lever thickness. The two locking levers have respective concave key-sweeps or key-engaging surfaces 55 at their lower side edge portions, and are similar except that the key-sweep of lever 49 projects farther than that of the other lever 50. The lever 49 is here shown to have an opening 56 which serves to facilitate handling of the lever and to distinguish the levers during assembly. Each lever has a shoulder 57 which bears against the inner periphery of the lock case to limit the spring-urged locking movement of the lever, and each lever also has a corner or projection 57' which is engageable with the inner periphery of the lock case to limit the movement of the lever in unlocking direction.

30 The other four plates on the pin 47 are ward members 58 and 59, two of each, which are interchangeable to produce key changes, the levers 49 and 50 being also interchangeable for this purpose. The ward plates have openings 60 through which the pin 47 passes, and are confined against rotation on the pin, each plate being provided with a finger 61 to engage the under side of the guide plate 27 and further provided with a finger 62 and a shoulder 63 to engage the inner periphery of the lock case. The ward plates 58 and 59 are similar except that each of the plates 59, Fig. 9, is provided with a notch 64 for key-clearance and to present a key-stopping shoulder 65.

45 The front case plate 16 and front wall of the shell are provided with respective openings 66 and 67 placed in alignment, each opening having a circular portion and a slot-like portion projecting downward from the circular portion. A slotted key guide or cylinder 68 is journaled in the openings 66 and 67 and has a peripheral flange 69 loosely fitting in the space between the front plate 16 and front wall of the shell. A key 70, preferably of the corrugated type, is adapted to enter the key guide and has bits 71 at various distances from the rotational axis of the key, some of the bits being engageable with the key-sweeps on the locking levers 49 and 50. The end of the key distant from the handle rotatably fits in a circular opening 72 formed in the rear case plate 17.

In assembling the padlock, the plates 27 and 41 and the pin 47 are riveted to the plate 16 of the cup-shaped lock case, and the case is then inserted into the shell 18, the key guide 68 having been placed in position. Two of the ward plates are placed on the pin 47, followed by the two spring-pressed lever plates 49 and 50 and the two remaining ward plates. The order of the several plates is varied in different locks so as to provide for key changes. Each spring 53 is inserted in the corresponding lever plate and flexed before this sub-assembly is placed in the case. The two locking lever plates are preferably placed centrally between the ward plates, so as to centrally en-

gage in the shackle notch, Fig. 5, but in some instances the lever plates may have different positions, provided they are still engageable in the shackle notch. The shackle and its spring means are then inserted, followed by the stud-carrying rear plate 17 and rear cover plate 22. The shell 18 is then spun over the cover plate to complete the assembly. The lever plates and their springs are retained against lateral shifting by the adjacent ward plates.

10 In operation, when it is desired to unlock the padlock, the key 70 is inserted into the rotatably mounted key guide 68, Fig. 4, the key being further guided by the offset end 46 of the plate 41 so as to enter the opening 72 in the rear plate 17, 15 and to prevent rotation of the key in the wrong direction. The key is then turned counter-clockwise, as viewed in Fig. 4, causing certain bits of the key to engage the concave edges or key-sweeps 55 of the locking levers and to turn these 20 levers on the pin 47 against the action of the springs 53 to the shackle-unlocking position seen in Fig. 4, the rotation of the key being stopped by the shoulders 65 on the ward plate 59. The shackle when released is moved outwardly to released position by its spring 38, and when released may be swung about its long leg as a pivot. If it is attempted to use a different key, having the key bits in other positions, the ward plates and locking levers will prevent unlocking movement. 25 In their unlocking position the lower corner 57' of at least one of the locking levers is close to the inner periphery of the lock case, so that if it is attempted to move the locking levers to unlocking position by a key having tumbler-engaging bits of about the same radius, only one of the levers will be released from locking position, the other remaining in locking position.

30 While the lock structure of the invention is here shown to be embodied in a padlock, certain 40 features of the structure are also applicable to other types of locks, such as door locks or cabinet locks.

What I claim as new and desire to secure by Letters Patent is:

45 1. In a lock, the combination of a lock case, a pin secured in said case, and a plurality of apertured plates mounted on said pin, one of said plates being pivoted on said pin and forming a locking lever adapted to be operated by a turnable key and to engage a lockable member, and another of said plates forming a ward member, said ward member having a key-stopping shoulder to limit the turning of the key in unlocking direction, and said plates being interchangeable on said pin to provide for key changes.

50 2. In a padlock, the combination of a lock case having a pivot member therein, an apertured guide member secured in said case, a shackle slideable in said lock case and in said guide member, a key-operated locking lever lockingly engageable with said shackle and swingable on said guide member, and a spring bearing on said guide member and urging said lever to locking position.

55 3. In a padlock, the combination of a lock case, a slidably guided shackle, a plate secured in said case and having an offset end portion presenting a key-guiding surface, spring means engaging said plate for urging said shackle outwardly, a key-operated locking lever in said case engageable with said shackle, and a key-guiding member rotatably mounted in said case.

60 4. In a padlock, the combination of an apertured lock case having a pivot member therein, an apertured guide plate secured in said case, a

shackle slidable in said lock case and guide plate, a key-operated locking lever engageable with said shackle and swingable on said pivot member, a ward plate mounted on said pivot member and engageable with said guide plate to prevent rotation of said plate, and a spring bearing on said guide member and urging said lever to locking position.

5. In a lock, the combination of a lock case having spaced outer and inner front wall portions with aligned openings, an apertured key-guiding member journaled in said openings and having an intermediate peripheral flange loosely confined between said wall portions, and key-operated locking means in said case. 5
